UNITED STATES PATENT OFFICE

AUGUSTA S. JOHNSON, OF BROOKLYN, NEW YORK.

CORSET-FASTENING MEANS.

Application filed November 20, 1922. Serial No. 602,194.

To all whom it may concern:

Be it known that I, AUGUSTA S. JOHNSON, a subject of the King of Sweden, and a resident of Brooklyn, in the county of Kings and State of New York, have invented certain new and useful Improvements in Corset-Fastening Means, of which the following is a specification.

The invention relates to improvements in corset fastening means, and has for its object a construction which will so hold the stays of a corset to which the usual clasps are attached, as to prevent tilting or buckling of the same, the gaping resulting therefrom, and the much annoying pinching of the flesh of the wearer, due to the present insecure clasping of the stays.

Another object is to provide a series of smooth surfaces next to the body of the wearer, eliminating sharp corners and edges and presenting substantially but one continuous surface, so that there is nothing upon which the garments of the wearer of the corset are liable to catch and tear.

I accomplish this result by placing in some of the spaces between the conventional clasps now used for fastening small projecting strips or tongues which overlap the outside of one of the stays and form a secure guide, thereby positively preventing the stays from tilting or buckling.

The invention will be understood more fully by reference to the accompanying drawings, in which—

Fig. 1 is an elevation showing a conventional form of corset stays equipped with the usual clasps and with my novel anti-tilting means;

Fig. 2 is a fragmentary elevation of the stay, drawn to a larger scale, with the anti-tilting means shown in a somewhat modified position;

Fig. 3 is a cross sectional view along the plane of line 3—3 in Fig. 2; and

Fig. 4 is a cross sectional view along the plane of line 4—4 in Fig. 2.

Like characters of reference denote similar parts throughout the several views and the following specification.

10 indicates a flexible front corset stay, and 11 a second and adjacent flexible stay. To these two stays or strips are attached a plurality of clasp members of conventional design and consisting of studs 12 and eyelets 13. Each stud 12 is riveted onto the stay 10 at 14 and is provided with a rounded

head 15 a slight distance above the outer surface of stay 10. Each eyelet 13 is riveted to the other stay 11 in juxtaposition to studs 12 by means of two small rivets 16. 60 Each eyelet is also provided with a key-hole aperture 17 consisting of a large round portion 18 of sufficient diameter to slip over head 15 of stud 12, and of relatively narrower part 19 to engage slidingly that body 65 portion of stud 12 which is located below its head 15 and the outer surface of stay 10.

Positioned between studs 12 and on the same stay 10 to which these studs are riveted, are small tongues 20, fastened to the 70 outside surface of the stay by, preferably, rivets 21. These tongues project over the adjacent stay 11.

Attention is particularly drawn to the fact that the studs 12, eyelets 13, and tongues 75 20 are all mounted on one and the same side of the stays, that is, the outside, leaving the inner surface, nearest to the body of the wearer, perfectly smooth.

The operation of my improved fastening means is as follows:

When the eyelet members and the stud members of the clasps and the tongues are attached to their respective stays and the stays themselves affixed in the usual way 85 to the corset body, each set of clasp members may be engaged, first one and then the other, down the length of the corset body. This is done by first inserting the head 15 of the stud 12 through the opening 18 of the 90 eyelet. When in this position care must be exercised to see that the tongues 20 slip over the outside surface of the stay 11. The stud 12 is then drawn either by hand of the wearer or by the natural expansion of 95 the body of the wearer of the corset toward and between the parallel sides of the narrow part 19 of the keyhole aperture 17. This operation is repeated until all studs and eyelets are thus engaged. 100

In this position, the eyelets and studs will be firmly locked together, and the tongues 20 will press against the adjacent stay 11 in such a manner, as to prevent any rocking or tilting movement of one corset stay with 105 respect to the other, or the gaping open of the stays, with the corresponding annoyance of pinching the flesh of the wearer. Attention is particularly called in this connection to the fact that the tongues 20 are fastened 110 to that stay which contains the studs 12, because, if they were fastened to the stay con-

taining the eyelets, the tongues would perform no function whatever, just like a disengaged eyelet, but, being brought in contact with the outside of the stay equipped with the eyelets, clearly prevents a tilting longitudinal movement when in position upon the body of the wearer.

While I have disclosed a preferred embodiment of my invention in the drawings, as attached to corsets, the same may be attached to any other form of garment where a similar means of fastening is desired. It is also obvious that my invention is susceptible of various minor changes in form and other details, such as for instance, the style of studs and eyelets which may be of any conventional style, and the method of attaching the tongues to the stays. So, for instance, while I have shown the tongues in Fig. 1, attached to the stay 10 midway between the studs, where this distance is relatively short, the same should, preferably, be located nearer to one stud than the other, as shown in Fig. 2, to allow easy slipping of the tongue over the outer surface of the stay 11 when closing the corset. Furthermore, while Fig. 1 shows a plurality of tongues fastened to the stay 10, in practice very often only one tongue at either end and between the fastening members has been found to accomplish the desired result very satisfactorily, and in other cases where the distance between the studs is relatively great, a plurality of tongues arranged between two adjoining sets of clasps has been used advantageously.

What I claim as new, is:

1. In combination with two adjacent corset stays, the one being equipped with

stud, the other with eyelets, for fastening purposes, tongues fastened to the said stay equipped with studs and projecting over and positioned between the said studs to project contactingly over the outside of the said other stay, before both studs, adjacent to each of the said tongues, have engaged their corresponding eyelets.

2. In combination with two adjacent corset stays, the one being equipped with studs, the other with eyelets, for fastening purposes, tongues fastened to the outside of the said stay equipped with studs and positioned between the said studs to project contactingly over the outside of the said other stay, before both studs, adjacent to each of the said tongues, have engaged their corresponding eyelets, the inner sides of the stays being perfectly smooth and devoid of any projecting members.

3. In combination with two adjacent corset stays, the one being equipped with studs, the other with eyelets, for fastening purposes, a tongue fastened to the outside of the said stay equipped with studs and projecting over and contacting with the outside of the said other stay, the said tongue being positioned on the one stay between the said studs and nearer to one of the studs than to the next one, the inner sides of the stays being perfectly smooth and devoid of any projecting members.

In testimony whereof, I have hereunto set my hand and seal in presence of two subscribing witnesses,

AUGUSTA S. JOHNSON. [L. s.]

Witnesses:
